(57) **CLAIM**

The ornamental design for a skateboard display rack, as shown and described.

DESCRIPTION

FIG. 1 is a left lower perspective view of a skateboard display rack illustrating my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a right lower perspective view of the skateboard display rack of FIG. 1 hanging on an exemplary wallboard and displaying a plurality of exemplary skateboards; and, FIG. 9 is a left lower perspective view of the skateboard display rack of FIG. 1 displaying a plurality of exemplary skateboards.

All dashed lines are for environmental purposes only and form no part of the claimed design.
